UNITED STATES PATENT OFFICE.

HENRY A. McCARTY, OF SAN FRANCISCO, CALIFORNIA, ADMINISTRATOR OF FRANCIS JOSEPH McCARTY, DECEASED, ASSIGNOR TO McCARTY WIRELESS TELEPHONE CO., OF SAN FRANCISCO, CALIFORNIA, A CORPORATION OF CALIFORNIA.

WIRELESS TRANSMISSION OF SONOROUS VIBRATIONS.

No. 867,896.

Specification of Letters Patent.

Patented Oct. 8, 1907.

Application filed September 20, 1906. Serial No. 336,397.

To all whom it may concern:

Be it known that FRANCIS JOSEPH McCARTY, deceased, formerly a citizen of the United States, residing in the city and county of San Francisco, State of California, invented new and useful Improvements in Wireless Transmission of Sonorous Vibrations, of which the following is a specification.

This invention relates to an apparatus by which sonorous vibrations may be transmitted without the aid 10 of wires or other mechanical intermediate connections between the stations.

It consists in the combination of devices, and in details of construction which will be more fully explained by reference to the accompanying drawings, in which— 15 the figure is a diagrammatic view illustrating the invention.

In this invention an induction coil is employed having a secondary winding A, and a primary winding 2. The secondary coil is connected in the usual manner 20 with the two sides of a spark gap 4.

The terminal 5 of the primary winding is connected to one pole of a dynamo D, and the other terminal 5^a of the primary winding is connected through an arc 6 to the other pole of the dynamo.

25 7 is a wire connecting with the center of the primary coil and uniting with the dynamo upon the same side with the wire 5^a; and within this connection 7 is an interrupter 8.

9 represents a magnetic blow-out which is energized 30 through the telephone transmitter 10 in circuit with a set of batteries as at 11. The magnetic blow-out is placed in close proximity to the arc 6.

The action in this apparatus is as follows: The current from the dynamo D is made to flow in the direction 35 of the arrow through half of the primary winding 2, thence through the connection 7, through the interrupter 8 and back to the dynamo, this being the shortest path and with less resistance than the path through arc 6. At the moment that the interrupter 8 breaks the 40 circuit, then the path through the arc 6 becomes momentarily the path for the current, which produces a steady magnetic field. This steady magnetic field produced in the primary by the current alternately flowing through the arc in unison with the breaks of the interrupter, serves to neutralize and govern the variations 45 of the magnetic field in the primary, which is produced by the interrupted circuit through 7. Consequently no discharge occurs as yet at spark-gap 4. But as soon as magnetic blow-out 9 is vocally energized through a 50 battery, the arc 6 is varied by the blow-out in unison

with the variations of the voice and this decreasing of the current in the circuit through the arc 6 by the modulations of the voice allows the variations of the magnetic field produced by the interrupted circuit along through 7 to gain the ascendancy and produce discharges at the spark gap in unison with the modulations of the voice.

Having thus described my invention, what I claim and desire to secure by Letters Patent is—

1. In an apparatus for the transmission of sonorous vibrations, a primary coil, a source of electrical energy with which it is connected, a secondary coil and spark-gap device, a return connection from the central portion of the primary coil, said return having an interrupter located within its length, and means located in the main portion of the primary circuit to independently vary the current flowing therethrough. 60

2. In an apparatus for transmitting sonorous vibrations a primary coil, a secondary coil and spark-gap devices, a source of electrical energy with which the primary coil is connected, a connection between the central portion of the primary coil and the source of electrical energy, an interrupter disposed in the circuit of the said intermediate connection, an arc light located in the main circuit of the primary and beyond the interrupter circuit, and 70 means whereby the impulses created by sonorous vibrations act to independently vary the vibrations in the circuit. 75

3. In an apparatus for transmitting sonorous vibrations, a primary coil, a source of electrical energy with which it is connected, a secondary coil energized by said primary coil having a spark-gap device, a return wire connecting with the central portion of the primary coil having an interrupter disposed in its circuit, an arc light located in the main circuit of the primary, a magnet contiguous to the arc, a telephone-transmitter, and electrically energized connection between the transmitter and the magnet. 80 85

4. In an apparatus for the transmission of sonorous vibrations, a primary coil, a source of electrical energy connections between said coil and the source of electrical energy, a secondary coil energized by the primary coil and having a spark gap device, an intermediate circuit connecting the central portion of the primary coil with the source of electrical energy, an interrupter located in said circuit, an arc light in circuit with the remainder of the primary circuit, a telephone transmitter, and an electrically energized magnet with which the transmitter is connected, said magnet being located in close proximity with the arc light. 90 95

5. In an apparatus for transmitting sonorous vibrations, a primary coil, a source of electrical energy from which currents are transmitted through the coil, a secondary coil energized by said primary and having a spark gap device, a circuit connecting the central portion of the primary coil with the source of electrical energy, an interrupter located in said circuit, an arc light located in the exterior portion of the primary circuit and normally neutralizing the variations of the magnetic field of the interrupted circuit. 100 105

6. In an apparatus for transmitting sonorous vibrations, a primary coil with means for transmitting an electrical current therethrough, a secondary coil, and a spark gap energized by said primary, a circuit connecting the central portion of the primary coil with the source of electrical energy, an interrupter disposed in said circuit, and controlled means located in that portion of the primary circuit exterior to the short circuit and varying the current of the short circuit. 35
10. 7. In an apparatus for transmitting sonorous vibrations, a primary coil, a source of electrical energy, a secondary coil, a spark gap device energized by the primary, a circuit connecting the central portion of the primary coil with the source of electrical energy, an interrupter disposed in the circuit, and vocally controlled means connecting with the main portion of the primary circuit for varying the current of the circuit. 40
15. 8. In an apparatus for transmitting sonorous vibrations, a primary coil, a source of electrical energy connected therewith, a secondary coil with a spark gap, said coil being energized by the primary coil, a circuit connecting the central portion of the primary coil with the source of electrical energy, an arc light located within the remainder of the primary circuit, an electro magnet located contiguous to the arc, a battery, and a telephone transmitter in circuit with the battery. 45
20. 9. In an apparatus for transmitting sonorous vibrations, an electrically energized primary coil, a source of electrical energy, a circuit connecting the central portion of the primary coil with the source of electrical energy and having an interrupter disposed in its circuit, an arc light located in the remainder of the primary circuit and acting to neutralize the variations of the magnetic field in the primary produced by the interrupted circuit, an electro magnet contiguous to the arc, and a telephone transmitter 50 and battery in circuit with the electro magnet. 55
25. 10. In an apparatus for transmitting sonorous vibrations, a secondary coil having a spark gap in circuit, an electrically energized primary coil, a source of electrical energy a circuit connecting the central portion of said coil with the source of electrical energy, an interrupter in said circuit, and means to normally neutralize the variations of the magnetic field of said primary and circuit, and a telephone transmitter and connections whereby the spark gap discharges are varied. 60
11. In an apparatus for transmitting sonorous vibrations, a secondary coil with spark gap device in circuit, an electrically energized primary coil, a source of electrical energy a return circuit connecting with the central portion of said coil, an interrupter located within said circuit, means for neutralizing the variations of the magnetic field of said circuit, a telephone transmitter and connections whereby the spark gap discharges are varied by vocal impulses through the transmitter. 65

In testimony whereof I, HENRY A. McCARTY, administrator of the estate of FRANCIS JOSEPH McCARTY, deceased, have hereunto set my hand in the presence of two subscribing witnesses.

HENRY A. McCARTY,
*Administrator of the estate of Francis Joseph McCarty,
deceased.*
